CABLE GUARD AND HOLDER RING

Lemuel W. Short, Beaverton, Oreg.

Application June 6, 1933, Serial No. 674,582

1 Claim. (Cl. 247—1)

The invention relates to a cable guard and holder ring and more especially to that kind for use with insulated wires for telephone, telegraph and low tension electric light and power lines, or signal wires.

The primary object of the invention is the provision of a device of this character, wherein maximum protection is had for current conductors, such as wires, cables or the like and of the insulated kind so that the insulation will not become mutilated when stress or strain is applied thereto resultant from high winds or from sharp objects thrown or blown, or from limbs of trees, or from squirrels or other animals chewing the insulation and additionally the lines will be shielded from weather elements, such as sleet, rain snow or the sun's rays.

Another object of the invention is the provision of a device of this character, wherein an electric current line overhead will be shielded and protected to the maximum and at the same time is readily accessible with resultant economical maintenance as the line in its construction does not require special workmen, such as cable splicers or other skilled mechanics for the erection and the maintenance of the guard and holder ring and different gauge wires are receivable in the guard for full measure of protection thereby.

A further object of the invention is the provision of a device of this character, wherein the guard is of a sectional kind so that the length of run thereof can be varied according to the need and when in position will be fully protected from the direct sun rays and inclement weather conditions, while the feed line of the electric system will be readily accessible for repair and maintenance, the device being susceptible of very flexible arrangement and having the advantage of giving a maximum ventilation to the line so as to relieve dampness under maintenance thereof.

A still further object of the invention is the provision of a device of this character which is extremely simple in its construction, thoroughly reliable and efficient in its purposes, strong, durable, readily and easily set up and removed with dispatch and inexpensive to manufacture and install.

With these and other objects in view, the invention consists in the features of construction, combination and arrangement of parts as will be hereinafter more fully described in detail, illustrated in the accompanying drawing, which discloses the preferred embodiment of the in-

vention, and pointed out in the claim hereunto appended.

In the accompanying drawing:

Figure 1 is a fragmentary side elevation of an electric feed cable showing the device constructed in accordance with the invention and applied thereto.

Figure 2 is an enlarged sectional view on the line 2—2 of Figure 1 looking in the direction of the arrows.

Figure 3 is an enlarged perspective view of one of the holder rings of the device.

Figure 4 is an exploded perspective view of the guard section.

Figure 5 is a vertical longitudinal sectional view showing a terminal part of the guard.

Figure 6 is a fragmentary perspective view of a branch or lead-off section of the guard.

Figure 7 is a plan view thereof.

Similar reference characters indicate corresponding parts throughout the several views in the drawing.

Referring to the drawing in detail, A designates generally a portion of an electric current lead, cable or wire and of the insulated kind, while overhanging the aerial disposition of this lead is the guard B formed of a plurality of sections 10, each being preferably made from sheet metal bent on itself into channel formation and of any desired length. Each section 10 at one end is outwardly offset and socketed at 11 for the interfitting therewith of the end 12 adjacent thereto of the next section and these interfitting portions of the adjacent sections of the guard are joined by fasteners 13, the end 12 being formed with opposite elongated slots 14 for the fasteners 13 so that there is a flexible or loose joining of these adjacent sections and a resultant overlap of the same at the joint.

The sections 10 of the guard B in their use are disposed with the channeled side opening downwardly for accommodation therein of the lead A. At intervals of the extent of the guard are holder rings C, each formed from a single length of wire bent intermediate thereof to provide a lead or saddle portion 15 and outwardly thereof at opposite sides open legs 16 for the reception of the sides of the sections 10 as is clearly disclosed in Figure 2 of the drawing. The ends of the wire are reversely twisted or bent to provide hanger hooks 17 and 18 respectively, these being detachably engageable in their reverse relation with a suspension cable 19 which is disposed above the lead A and the guard B as is clearly shown in Figure 1 of the drawing.

This cable 19 at distant points with respect to each other is suspended taut and thus with the rings C the lead A and the guard B under assembly will be held. The guard B will protect the lead A from weather elements and also from direct sun rays. By reason of the formation of the holder ring C there can be no rubbing or chaffing of the insulation of the lead and the guard will shield such insulation from attack of small sharp objects thrown or blown in the air or from limbs of trees or from squirrels and other animals that are liable to chew the lead sheath.

15 In Figure 5 of the drawing the section 20 of the guard has connected therewith a terminal piece 21 for a lead-off for the lead A.

In Figures 6 and 7 of the drawing the section

22 of the guard has integrally formed therewith a branch extension 23 which also is a lead-off to the guard for the lead A.

What is claimed is:

A device of the character described comprising a sectional overhanging guard having the ends of the sections flexibly interfitting with each other, a hanger for the guard and including a single length of wire bent on itself intermediate its ends to form a half-circular saddle for a cable and U-shaped legs at opposite sides of the cable for accommodating opposite sides of the guard, and hook-like reversely disposed terminals on said legs for latching engagement with a suspension medium superposed with relation to said guard. 80 85 90
